SPRING CATCH

Millard F. Saxton, Flint, and Charles S. Comey,
Ferndale, Mich., assignors to The Engineered
Products Co., Flint, Mich., a corporation of
Michigan

Application August 17, 1950, Serial No. 180,052

8 Claims. (Cl. 292—71)

1

This invention relates to a spring catch and, more particularly, to a spring catch of the type commonly used on doors.

It is an object of this invention to produce a spring catch, the construction of which permits its economical manufacture and, at the same time, enables the unit to be mounted in a variety of different positions to meet the requirements of various types of installations.

It is a further object of this invention to produce a catch which will operate for a long time with a minimum amount of wear and with a minimum amount of noise.

A further object of this invention resides in the provision of a catch which is biased by a light spring and a heavy spring, the one spring resisting the door opening operation and the other spring resisting the door closing operation.

A further object of this invention is to provide a catch and handle assembly which is attractive in appearance and readily mounted on a door or the like and which lends itself to economical manufacture.

Other objects in the way of simplicity of manufacture and operation of the catch and its adaptability for different installations will become apparent in the following description taken in conjunction with the accompanying drawings in which

Fig. 1 is a side elevation of the basic catch unit of this invention.

Fig. 2 is an end view of the catch.

Fig. 3 is a sectional view of the catch showing the internal construction thereof.

Fig. 4 is a side elevation, partly in section, of the catch unit assembled with a mounting flange for a mortised installation.

Figs. 5, 6, 7, 8 and 9 illustrate the operation of the catch when a door on which it is mounted is opened and closed.

Fig. 10 is a fragmentary perspective view of the catch illustrating one form of installation thereof.

Fig. 11 is a fragmentary view, partly in section, of the catch combined with a handle for use on a door, such as a screen door.

Fig. 12 is an end view of the assembly shown in Fig. 11.

Fig. 13 is a sectional view taken substantially along the lines 13—13 in Fig. 11.

Fig. 14 illustrates another form of catch and handle assembly mounted on a door.

Fig. 15 is an end view of the catch and handle assembly shown in Fig. 14.

2

Fig. 16 illustrates another form of catch and handle assembly for use on a door.

Fig. 17 is an end view of a catch and handle assembly shown in Fig. 16.

Fig. 18 illustrates another form of catch and handle assembly.

Fig. 19 is a sectional view along the lines 19—19 in Fig. 18.

Fig. 20 shows the manner in which the catch 10 of this invention is adapted for use as a door stop.

Referring to the drawings and particularly to Figs. 1 through 3, the basic form of the catch of our invention is there illustrated. The catch 15 generally comprises a tubular or cylindrical casing 10 which is generally in the form of a cup-shaped member having an opening 12 at one end thereof. Within casing 10 there is slidably arranged a hollow piston 14 having an opening 16 which corresponds and is aligned with opening 12 in casing 10. Within piston 14 there is arranged a bolt generally referenced 18 having an enlarged body portion 20 housed within piston 14 and a nose piece 22 normally projecting outwardly through openings 12 and 16.

Bolt 18 is biased to the projected position illustrated in Fig. 3 by a spring 24 which backs at one end against the inner face of bolt 18 and at the other end against a washer 26 which is retained within piston 14 as by inwardly crimping the end of the piston as at 28. Piston 14 is in turn biased towards the end of casing 10 having the opening 12 by a spring 30 which is arranged between washer 26 and a cover plate 32 which is crimped in place at the other end of casing 10.

The nose piece portion 22 of bolt 18 is wedge shaped and has one face 34 extending generally parallel to the axis of piston 14 and its opposite face 36 inclined to the face 34. We have found that a very quiet operation is obtained with the bolt 18 formed of plastic of sufficient strength to withstand the use to which catches of this type are normally subjected. A plastic material which we have found to be admirably suited for the manufacture of bolt 18 is molded nylon and more particularly a linear polyamide such as is disclosed in U. S. Patent No. 2,130,523. This type of plastic is a thermo-plastic material with a high melting point, remarkable strength and has a natural lubricating quality which properties we have found make it ideal for use as a bolt in a door catch. Plastic materials in general also have the advantage over metal in that they are of lighter weight, possess high

dimensional fidelity and are adapted for easy fabrication.

One of the important features of the catch of our invention resides in the provision of springs 24 and 30. Spring 24, it will be noted, is considerably heavier than spring 30, and it is therefore obvious that the resistance to axial movement of piston 14 within casing 10 is much less than the resistance to the pivotal movement of bolt 18 within piston 14. It will be noted that there is sufficient clearance between the body portion 20 of bolt 18 and the interior walls of piston 14 to permit the bolt 18 to pivot around the edge 33 of the bolt. Springs 24 and 30 are selected such that, when they are crimped into place in the assembly, they are subjected to an initial compression. These springs are arranged under initial compression so that a low-rate spring may be used and so that the force necessary to compress the springs is more uniform.

As will be more fully described hereinafter, the basic assembly thus far described is adapted to be used in a variety of installations and, for the purpose of illustrating the operation of the catch, there is shown in Fig. 4 the form of catch which may be employed for a mortised installation. The catch illustrated in Fig. 4 is constructed generally along the lines of that illustrated in Figs. 1 through 3. For the purposes of economy, however, the casing 40 is formed slightly different from the casing 10. Casing 40, like casing 10, is fashioned as a cup-shaped member but is provided with an outwardly extending radial flange 42 around the open end thereof. Over the open end of casing 40 there is arranged a mounting flange 44 and a face plate 46, which is apertured to receive casing 40 and which is inserted over the casing from the rear end thereof so that the radial flange 42 is held between the mounting flange 44 and the face plate 46. The entire assembly is held together by crimping the metal of the mounting flange 44 around the screw holes 48 over adjacent portions of the face plate as at 50. Mounting flange 44 is provided with a central aperture 52 through which the nose piece 22 of bolt 18 normally projects.

The assembly illustrated in Fig. 4 can be mounted on a door by simply drilling a hole 54 (Fig. 5) in the vertical edge of the door, the hole being of a size to accommodate casing 40. The door jamb is fitted with a conventional striker plate 56 having a curved outer flange 58 which cooperates with the face 36 of nose piece 22 in the door closing operation and a substantially straight keeper flange portion 60 which cooperates with the face 34 of nose piece 22 in the door opening operation.

Figs. 5 through 9 illustrate the unique operating features of the catch of this invention. Face 36 of nose piece 22 is inclined to the axis of piston 14 such that, when the door is closed, flange 58 of striker 56 engages face 36 and tends to shift the bolt 18 axially inwardly of the catch as is illustrated in Fig. 6. Since spring 30 is much lighter than spring 24, the entire piston assembly will be shifted axially inwardly of casing 40. When the door reaches the fully closed position nose piece 22 is released by the striker 56 and the piston assembly is projected outwardly under the influence of spring 30. Striker 56 is mounted on the door jamb such that, when the door is in closed position, bolt 18 is disposed directly behind keeper flange 60 and the engagement of keeper flange 60 with the face 34 of the bolt thus maintains the door in a closed condition. Opening of

the door is thereby resisted by the engagement of face 34 of bolt 18 with the keeper flange 60. Face 34 extends generally axially of the axis of piston 14 and therefore, when the door is opened, keeper flange 60 does not tend to shift the bolt axially inwardly of the casing but rather to pivot the bolt around the edge 38 of the body portion 20, as is illustrated in Fig. 8.

The pivotal movement of the bolt within piston 14 is resisted by spring 24 and it is therefore obvious that, until the bolt pivots to a position where the nose of the bolt clears the flange 60 of striker 56 considerably, more force must be exerted upon the door in the opening operation than is required for closing the door. When the door is open to the extent indicated in Fig. 9, the nose of the bolt rides over keeper flange 60 and the bolt thereby springs back to the position shown by broken lines in Fig. 9 projecting fully out of the end of piston 14. This return of the bolt causes piston 14 to move axially inwardly of the casing against the resistance of spring 30. The relative forces required to open and close the door on which the catch is mounted can therefore be controlled by varying the relative strengths of springs 24 and 30. It will also be appreciated that if the catch is used in an installation where it is desired to require more force to close the door than to open it, the desired result may be obtained by replacing spring 24 with a light spring and spring 30 with a heavy spring.

The basic catch assembly illustrated in Figs. 1 through 3 is adapted to be used in a variety of applications, and it is not limited to the installation shown in Fig. 4. A simple installation for use on the inner face of a door is shown in Fig. 10 wherein the basic catch assembly is secured to the face of the door by a cylindrical bracket 62 which is fashioned with a pair of overlying mounting flanges 64 and 66. The cylindrical portion 68 of bracket 62 is dimensioned such as to receive the casing 10 with a rather close fit when flanges 64 and 66 are spaced apart slightly. Bracket 62 is secured to the face of the door as by screws 70. When the catch is mounted on the door, flanges 64 and 66 are brought together by tightening the screws 70, and casing 10 is thereby gripped firmly by the cylindrical portion 68 of bracket 62.

A suitable striker plate 72 is mounted on the door jamb for cooperation with the nose piece 22 of the bolt. It will be observed that, by forming casing 10 as a cylinder, the catch can be used as either a right-handed catch or a left-handed catch by inserting the casing through the cylindrical portion 68 of bracket 62 in the proper direction. The catch can also be rotated to any desirable position to meet the requirements of a variety of different types of installation.

The cylindrical shape of the catch adapts the catch for mounting on a door in combination with a handle member. In Figs. 11 through 13, for instance, there is shown a combined catch and handle assembly which is admirably suited for use on a screen door. In this form of the invention the cover plate 32 is replaced by a cover plate 74 which is centrally apertured as at 76. Within aperture 76 there is slidably arranged a pin 78 having a plate 80 secured to one end thereof and against which the inner face of bolt 18 abuts. Pin 78 is disposed within piston 14 and is biased on the one hand by spring 24. Pin 78 is also biased by a relatively light spring 82 to a position in which it projects the nose piece 22 of bolt 18 outwardly through the openings 12 and 16. It will be observed that in the form of catch

illustrated in Fig. 11, the heavy spring 24 resists the movement of plate 88 relative to piston 14 and inward movement of the piston relative to casing 10 is resisted by light spring 82.

On the outer face of cover plate 74 there is pivoted, as at 84, a cap 86 having a central aperture 88 which in one position of the cap is aligned with opening 76 in plate 74. In said last mentioned position, pin 78 is capable of being projected through openings 76 and 88 by pivotal or axial movement of bolt 18 when the door is opened. Cap 86 is, however, pivotable to a position (shown by broken lines in Fig. 13) wherein the opening 88 is offset relative to the opening 76. In this position the face 90 of the cap blocks, or at least partially blocks, opening 76 to prevent pin 78 from being projected outwardly of the casing and thereby prevent opening of the door. Face 90 of cap 86 has an extending arm 91 which is bent inwardly to project through an arcuate slot 94 in cover plate 74, slot 94 having a notch in which a projection 96 on arm 91 is adapted to engage to yieldably hold cap 86 in the unlocked position. A pair of upstanding flanges 98 along each side of face 90 form finger pieces which enable the cover plate 86 to be conveniently actuated.

It will be appreciated that the form of catch illustrated in Figs. 11 through 13 may be employed whenever it is desired to provide a catch with a locking feature. In the particular embodiment illustrated in these figures, the catch is associated with a handle 100 which is fashioned as a stamping having a substantially flat mounting portion 102 which connects with one end of a looped handle portion 104. The other end of the handle portion 104 is fashioned into a pair of spaced apart legs 106 provided with mounting flanges 108 at the lower ends thereof and connected by a semi-cylindrical portion 110 which conforms in shape and size with cylindrical casing 10. The assembly is adapted to be secured to the face of a door by screws 112 or other fastening devices which, when driven into the door, clamp the casing 10 between the face of the door and the arcuate connecting portion 110 of the handle.

In Figs. 14 and 15 the catch assembly is shown mounted on a modified form of handle which includes an arcuately shaped handle portion 114 on the outside of the door and a somewhat similarly shaped handle portion 116 on the inside of the door. Handle members 114 and 116 are of arcuate cross section as is better shown in Fig. 15. A pair of threaded ferrules 118 are peened or otherwise suitably secured to the base portion 120 on handle member 116, and the base portion 122 of handle member 114 is suitably apertured for reception of threaded studs 124 which may be inserted into suitable openings in the door for engagement with the threaded ferrules 118. The base 120 of handle member 116 is provided with an arcuate seat 126. Casing 10 is retained on seat 126 by a strap member 128 which overlies the casing and has its lower edges 130 bent to underlie the lateral edges of base 120. Strap 128 is fashioned with an upper rear portion which interfits with the arcuate cross sectional contour of handle member 116 and which is secured to the handle as at 130.

In Figs. 16 and 17 there is illustrated another form of catch and handle assembly in which the handle is fashioned as two similarly shaped half members 132 and 134 which are secured together as by rivets 136. Each half portion 132 and 134 is shaped to provide a handle portion 138 and

an arcuately shaped leg portion 140 which terminates at its lower edge in a mounting flange 142. These half sections are dimensioned such that the arcuate leg portions 140 snugly receive the cylindrical casing 10 and maintain the catch rigidly in position on the door. If desired, each leg portion 140 may be provided with an arcuately inwardly struck tab 144 which engages the casing 10 around a portion thereof adjacent the face of the door.

In Figs. 18 and 19 another form of catch and handle assembly is illustrated. In this embodiment the handle 146 has a flat base portion 148 adapted to be arranged against and secured to the face of a door. Along one edge base 148 is fashioned into an upstanding face plate 150 which terminates in a pull portion 152 which extends generally parallel to the base 148 but is spaced therefrom. Pull portion 152 and base 148 are spaced apart sufficiently to permit mounting of the catch therebetween. The catch is mounted on base 148 by a U-shaped mounting bracket 154 having mounting flanges 156 along each edge thereof. The upstanding face plate 150 is suitably apertured as at 158 to receive casing 10 so that the nose piece 22 may be arranged to project into an engagement with a striker plate 160. A dead bolt 162 is slidably arranged on bracket 154 as by a headed pin 164 slidable within an elongated slot 166 in bracket 154. Dead bolt 162, when in the projected position, cooperates with striker plate 160 to prevent opening of the door.

In Fig. 20 there is illustrated an arrangement wherein the catch of this invention is employed as a combined door stop and door holder. The catch is mounted in an upstanding position on the floor by means of a cylindrically shaped bracket 168 which is dimensioned to snugly receive casing 10. In this arrangement the catch is positioned with the nose piece 22 projecting upwardly for engagement with a striker 169 which is secured to the door at the proper height. By arranging the casing 10 such that the flat face 34 of the nose piece engages behind the striker 169 when the door is fully opened and by suitably selecting the springs 24 and 30, the operation of the door may be controlled such that little effort is required to swing the door open into engagement with the catch but considerable force is required to swing the door out of engagement with the catch when it is desired to close the door. A rubber sleeve 170 is slipped over casing 10 and bracket 168 to serve as a bumper for the door.

It will thus be seen that the catch of this invention may be employed advantageously in many types of installations. The cylindrical shape of the basic catch assembly greatly facilitates the adjustment of the catch in the desired position for the particular installation employed. The cylindrical shape also adapts the catch for convenient mounting in combination with a handle member. The catch is furthermore of a design which admits of economical manufacture.

One of the important features of the catch of this invention resides in the shape of the nose piece 22 of bolt 18 in combination with the piston assembly and the spring of different weights. By arranging the nose piece such that its pivotal movement is resisted by a relatively heavy spring and its axial movement by a relatively light spring, the small force required to close the door results in a very quiet operation. The inability to produce quiet operation is one of the main objections to spring catches of the conventional

type. The quiet operation of the catch is further enhanced by the use of the thermo-plastic material for forming the nose piece.

We claim:

1. A door catch comprising a tubular casing, a piston disposed substantially completely within said casing, said casing and piston having registering openings in one set of corresponding end walls thereof, a bolt having an enlarged body portion within said piston and having a reduced nose piece projectable through said registering openings, a spring acting between said body portion of the bolt and piston and biasing said bolt such that the nose piece normally projects outwardly of said opening in said piston and said body portion abuts against said end wall of said piston, a second spring acting between said bolt and said casing and biasing said piston towards said end wall of said casing, said first spring being heavier than said second spring, said bolt being rockable in said piston by engagement of an edge portion of said enlarged body portion with the inner face of said end wall of the piston adjacent said opening therein and being arranged to stress said first spring when pivoted and to stress said second spring when shifted axially of said casing.

2. The combination set forth in claim 1 including a pin in said casing, said pin being axially shiftable in response to movement of said bolt, and means on said casing releasably engageable with said pin for preventing the axial shifting thereof.

3. The combination set forth in claim 2 wherein said casing is provided with an opening at the other end thereof to which said pin is projectable by a movement of said bolt and wherein said last mentioned means comprises a finger actuated member on said casing for obstructing the opening in said other end of said casing and thereby preventing the axial shifting of said pin.

4. A friction catch comprising a tubular casing, a tubular piston disposed substantially completely within the confines of said casing and slideable axially therein, means defining an end wall at one end of said casing, said piston having an end wall at the corresponding end thereof, said end walls each having an opening therein smaller in size than the cross section of the respective members, said openings registering in a direction axially of said casing, a bolt having an enlarged head portion received within said piston and a reduced nose piece projectable through said registering openings, a coil compression

spring acting between said piston and the opposite end of said casing and urging the piston into abutting relation with said end wall of said casing, a coil compression spring acting between 5 said bolt and piston and biasing said bolt axially toward said end wall of said piston so that the head portion of the bolt abuts against said end wall and said nose piece projects outwardly through the opening in said end wall, said head portion of said bolt having a rim extending radially outwardly beyond said nose piece and normally abutting against the inner face of said end wall of said piston around the opening therein, said bolt being rockable in a direction inwardly of said piston by engagement of a portion of said rim with a portion of said end wall of said piston, said second mentioned spring engaging the inner end of said bolt and yieldably resisting such pivotal movement, said springs being 10 selected such that a greater force is required on said nose piece to rock said bolt inwardly of said piston than is required to shift said bolt and piston axially towards said opposite end of said casing.

25 5. The combination set forth in claim 4 wherein in said rim is provided with a peripheral edge portion which is rounded in an axial direction.

6. The combination set forth in claim 4 wherein in said registering openings are generally rectangular in shape and wherein said nose piece is correspondingly shaped in transverse section.

7. The combination set forth in claim 4 wherein in said casing is of cylindrical shape.

8. The combination set forth in claim 4 wherein in the outer end of said nose piece is provided with an axially extending face on one side thereof and with a face inclined to said axially extending face on the opposite side thereof.
